UNITED STATES PATENT OFFICE.

FRANK DETTE, OF LYNN, MASSACHUSETTS.

DESIGN FOR A COAT.

46,630.

Specification for Design.

Patented Nov. 10, 1914.

Application filed July 2, 1914. Serial No. 848,686. Term of patent 3½ years.

To all whom it may concern:

Be it known that I, FRANK DETTE, a subject of the King of Italy, residing at Lynn, in the county of Essex and State of Massachusetts, have invented a new, original, and ornamental Design for a Coat, of which the following is a specification, reference being had to the accompanying drawing, forming a part thereof.

The figure is a front view of a coat, showing my new design.

I claim:

The ornamental design for a coat, as shown.

In testimony whereof I have affixed my signature, in presence of two witnesses.

FRANK DETTE.

Witnesses:

JENNIE ROBICHAND,
LILLIAN V. JOHNSON.
